CLAIM

The ornamental design for an exhibition stand as shown and described.

DESCRIPTION

FIG. 1 is a front view of an exhibition stand showing an embodiment of the claimed design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a right front perspective view thereof;

FIG. 8 is a left rear perspective view thereof;

FIG. 9 is a front view of an exhibition stand showing another embodiment of the claimed design;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a right front perspective view thereof; and,

FIG. 16 is a left rear perspective view thereof.

The broken lines illustrate unclaimed features that do not form a part of the embodiment, and the broken lines form no part of the claimed design.

1 Claim, 16 Drawing Sheets
